UNITED STATES PATENT OFFICE.

MAXWELL E. RAMSEY, OF ST. LOUIS, MISSOURI.

BED.

Application filed April 8, 1925. Serial No. 21,457.

This invention relates to foldable beds.

An object of the invention is to provide a foldable bed designed and adapted for various uses and having special advantages for 5 use as an undertaker's dressing bed, although the utility of the device is by no means restricted to such specific use.

Another object of the invention is to provide an adjustable and foldable bed having 10 a head portion adjustable in different positions with respect to the remaining portion of the bed, and having novel cooperative relationship to the bed frame so that all of the intended objects and advantages of the 15 invention are conveniently obtainable.

Other objects of the invention will appear from the following description, reference being made to the drawing in which

Fig. 1 is a plan view of my improved 20 bed.

Fig. 2 is a side elevation.

Fig. 3 is a sectional view of the bed frame on the line 3—3 of Fig. 1.

Figs. 4, 5 and 6 are views showing the 25 manner in which the longitudinal portion of the bed frame is connected with the end frames.

The embodiment of the invention shown is designed and adapted specially for use 30 as an undertaker's dressing bed, though, as will hereinafter appear, the invention may be used for other purposes with equal satisfaction. As shown, the end frames 1 may be of any desired configuration or design 35 and are supported upon caster rollers 2. To each upright side member of each end frame a plate 3 is removably attached by screws 4 and each plate supports a knob 5.

The horizontal portion of the bed is an 40 adjustable and foldable structure and comprises at the foot a pair of horizontal side members 6 each of which is composed of angle iron, the respective flanges of which are vertical at the sides and extend horizontally 45 inwardly at the top. The angle iron side members 6 have their forward ends connected by a transverse frame member 7, the ends of which are attached to the inwardly extending horizontal flanges of the side 50 members and the intermediate portion of which is bowed downwardly to obtain the benefit of the resilient characteristics of the supporting frame. The outer ends of the members 6 are connected by a cross bar 8. 55 A plate 9 is supported at each end of the cross bar 8 and each of said plates is pro-

vided with a hole 10 of sufficient size to permit insertion and withdrawal of the knobs 5 in the assembly and dismantling of the bed. From the holes 10 slots 11 extend upwardly permitting the stems or shanks of the knobs 5 to enter therein to hold the horizontal portion of the bed in rigid connection with the foot frame. In order to detach the horizontal portion from the foot frame it is only necessary to raise the horizontal portion slightly to permit the knobs 5 to be withdrawn through the holes 10.

Inclined braces 12 connect the upper ends of the plates 9 with the side members 6. The 70 plates 9 are of angle iron, as will be understood by reference to Fig. 6, thus permitting the upper ends of the braces 12 to be connected to the forwardly extending flanges 75 of the plates 9.

The side members 6 of the rear portion of the bed frame are connected by transverse resilient metallic strips 13, the forward one of which is connected with the rear cross connection 8 by longitudinal resilient strips 14. The strips 13 and 14 are interlaced to provide a woven resilient frame structure sufficiently above the rigid transverse bar 7 to obtain the benefit of the resilient characteristics of said resilient frame.

The supporting portion of the front end of the horizontal frame includes a pair of horizontal side members 15 composed of angle iron, the rear ends of which are overlapped by the front ends of the frame member 6 and are pivoted thereto by pivots 16 permitting the frame members 15 to be folded downwardly and rearwardly against the under side of the rear portion of the bed frame. The front ends of the side members 15 are connected by a transverse angle iron bar 17 supporting angle plates 18 similar in all respects to the plates 3 and having knobs 19 corresponding to the knobs 5. The plates 18 have holes and slots corresponding to the holes 10 and slots 11 for similar purposes.

An adjustable mattress supporting frame is pivotally connected to the frame members 15 and comprises a pair of angle iron side members 20, the rear ends of which are connected to the members 15 by pivots 21 and the front ends of which are connected by a transverse bar 22. In their lower positions the angle iron side members 20 have their horizontal flanges resting upon the upper horizontal flanges of the angle iron mem-

bers 15. A resilient metallic strip 23 connects the side members 15 between the rear ends of the adjustable frame members 20 and the forward ends of the frame members 6, and 5 a number of longitudinal strips 24 connect the strip 23 with the bar 22 and are arranged in alinement with the longitudinal strips 14. A number of transverse resilient strips 25 connect the frame members 20 and 10 are interlaced with the strips 24 to provide a resilient woven frame.

A pair of angle iron arms 26 have their rear ends connected by pivots 27 with the side members 20 and have their forward 15 ends connected by a transverse rod 28. The lower edges of the vertical flanges of the arms 26 are provided with notches 29 designed and adapted to engage upon a downwardly bowed transverse rod 30 connecting 20 the side frame members 15. It is apparent that this arrangement permits the pivoted head frame to be raised to and supported in different angles of inclination or placed horizontally, as desired.

25 From the foregoing it will be seen that my improved bed may be constructed of light and very strong metal so that it is easily portable, may be easily assembled and dismantled, and is therefore highly useful as 30 an undertaker's dressing bed. However, the

utility of the device is not restricted to such use, as it is satisfactory for general purposes.

What I claim and desire to secure by Letters Patent is:—

A bed comprising angle iron side frame members each having one of its flanges vertical and its other flange extending horizontally inwardly from the upper edge of said vertical flange, a resilient strip connecting said horizontal flanges of said frame members, a pair of angle iron side frame members having their rear ends pivoted to the respective first named frame members a short distance in front of said resilient strip and having vertical flanges movable downwardly 45 between the inner edges of said horizontal flanges of said first named frame members and having outwardly extending horizontal flanges arranged to rest upon said horizontal flanges of said first named frame members in one position of said second frame members, a series of resilient strips 50 having their front ends connected to said second frame members and their rear ends connected to said resilient strip, and means 55 for supporting said second frame members parallel with each other and in different angles of inclination relative to said first named frame members.

MAXWELL E. RAMSEY.
